UNITED STATES PATENT OFFICE

108,829

DESIGN FOR A TEXTILE FABRIC

Theresa Emmerich, New York, N. Y.

Application February 4, 1938, Serial No. 74,869

Term of patent 3½ years

To all whom it may concern:

Be it known that I, Theresa Emmerich, a citizen of the United States of America, residing in city of New York, county of New York, and State of New York, have invented a new, original, and ornamental Design for a Textile Fabric, of which the following is a specification, reference being had to the accompanying drawing, forming part thereof. The figure on the drawing is a plan view of a textile fabric showing my new design.

I claim:

The ornamental design for a textile fabric, substantially as shown.

THERESA EMMERICH.
